(57) **CLAIM**

An ornamental design for a height adjustable desk as shown and described.

DESCRIPTION

FIG. 1 is a first perspective view of a height adjustable desk showing the design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a first portion of FIG. 1; and, FIG. 10 is an enlarged view of a second portion of FIG. 1. The dot-dash broken lines encircling portions of the height adjustable table in FIG. 1 and illustrated in enlarged views in FIGS. 9 and 10 form no part of the claimed design. The dash lines depict portions of the height adjustable desk and form no part of the design.

1 Claim, 10 Drawing Sheets
